UNITED STATES PATENT OFFICE.

GEORGE J. BICKNELL, OF BOSTON, MASSACHUSETTS.

FABRIC AND METHOD OF MAKING THE SAME.

1,273,815.

Specification of Letters Patent. Patented July 30, 1918.

Application filed March 14, 1914, Serial No. 824,806. Renewed December 14, 1916. Serial No. 137,055.

To all whom it may concern:

Be it known that I, GEORGE J. BICKNELL, of Boston, in the county of Suffolk and State of Massachusetts, have invented certain new and useful Improvements in Fabrics and Methods of Making the Same, of which the following is a specification.

This invention relates to the manufacture of light thick fabric adapted for the making of warm garments or for such uses as those to which quilts, comforters or "puffs" are applied, or which may be cut to any sizes desired and used for sanitary absorbent pads. The first mentioned articles are usually made by basting together two layers of cloth with an intermediate layer of cotton, wool, or down, while the absorbent pads usually comprise a layer of absorbent cotton batting simply spread between two pieces of cheese cloth or gauze, basted together.

The object of my invention is to provide a woven fabric capable of use for any or all of the purposes mentioned, the soft fluffy material being so held that it is not, and can not become, locally bunched, but always remains equally distributed throughout the entire area of the fabric be it large or small without unfilled portions or areas, so as to afford uniform protection when employed as a comforter or "puff", or for making garments, and to provide for uniform taking up of moisture when employed for absorbing purposes on hospital cots or elsewhere.

To these ends, the invention consists in the improvements which I shall now proceed to describe and claim.

Figures 1 and 2 represent respectively longitudinal and transverse sections of a fabric constructed according to my invention;

Fig. 3 is a plan view of a piece of the fabric;

Fig. 4 represents a section on line 4—4 of Fig. 2;

Fig. 5 is a view similar to Fig. 4, of a modification.

All of the figures are drawn to an enlarged scale.

The fabric shown in Figs. 1 to 4, inclusive, comprises two sets of warp threads 1 and 2, two sets of weft threads 3 and 4, a set of tie warps 2^a, and a plurality of longitudinal fluffy padding strands 5 herein shown as loose slivers or rovings of carded fibers. The two sets of warp threads 1 and 2 are controlled by the harnesses of the loom in which the fabric is woven so as to provide two

sheds *a* and *b* for the shuttles by which the weft threads 3 and 4 are laid therein during the operation of the loom, the weft thread 3 being laid in shed *a* exclusively and weft thread 4 in shed *b* exclusively with the result that two superimposed fabrics A and B are simultaneously produced.

The tie warps 2^a are controlled by a separate harness frame which is so operated as to lift said warps into the upper half of shed *a* at predetermined intervals during the operation of the loom and at other times to maintain said stitching warps depressed within the shed *b*. As shown in Fig. 70 these stitching warps 2^a are lifted into the shed at every fourth pick of the loom and remain there for only one pick after which they are returned to the shed *b* within which they remain for three successive picks before they are again raised into shed *a*. In this way as the two fabrics F and B are woven they are tied together longitudinally, not only between the roving or sliver padding-strands 5, but at each selvage 6 also as will be clear from Figs. 2 and 3.

In order to draw the two fabrics F and B together between the padding strands 5 and at the selvages 6, the stitching warps 2^a 85 may be supplied from a separate warp beam under sufficient tension other than is maintained upon the warps 1 and 2, so that the exterior of the finished padded fabric has a "quilted" or corrugated shape and appearance.

The padding strands 5 may be led from the supply into position between the two sets of warps 1 and 2, past the harnesses and reel specially constructed or arranged to permit of this, and so as to be incorporated in the fabric as it is produced, each strand occupying a tubular compartment of its own formed in the fabric by the tie warps 2^a which are raised and lowered from one 100 shed to the other through the spaces between said strands 5.

In Fig. 5 I have shown a modified structure which differs from that already described only in the provision of two sets of tie warps 2^b and 2^c which are simultaneously but oppositely shifted from one shed to the other every second pick of the loom.

When my fabric is to be made into a garment, and it is desired to have the outside 110 of one color or character and the inside of another color or character, this requirement

may be met by employing threads 1 and 3 of a color or character appropriate to the outside of the garment and threads 2 and 4 appropriate to the inside thereof. In such cases I prefer to resort to another feature of this invention which consists in also employing tie warps 2^a, or 2^b and 2^c, of the same color or character as the threads 1 and 3 of the outside fabric. In this way the 10 loops of the tie warp or warps which are incorporated in the outside of the garment will be of the same color or character as the latter.

The strands 5, if composed of such loosely assembled fibers as to render the strands liable to unduly pull out or lengthen during the weaving operation, may be suitably reinforced as by means of longitudinal threads 7.

20 I employ the term "roving" herein for the purpose of description and not of limitation; that is, the term is intended to apply to any strands of loose fluffy material whether known by the specific terms "roves", 25 "slivers" or strips cut from batting, or strands of any material which will provide a soft, fluffy, filling or stuffing between the two woven fabrics. Nor do I limit myself to any such proportions as indicated in the 30 drawings; for instance the roving may be of greater relative width, or greater relative thickness, than illustrated, and the tie warps may pass through at greater or lesser intervals.

35 It will now be readily understood that while my improved compound fabric may be manufactured in such widths as are suitable for the making of such articles as quilts, comforters or "puffs", without requiring any sewing other than to hem or otherwise finish the cut edges, the fabric can be readily cut according to patterns for the making of vests, coat linings, or other apparel uses, or to provide absorbent pads. 40 My improved fabric is especially adapted

to the last mentioned use, where expedition is often required in the preparation of a pad because a pad of the desired size can be quickly cut from a sheet of the material kept in stock without risk of the soft filling becoming displaced. And all the cutting required to make a pad may be accomplished in one-third of the time that is required to cut out two pieces of cheese cloth and a piece of batting. The pad thus cut may be 55 treated as an integral structure, with no liability of relative displacement of its parts, and having no unfilled spaces or areas.

Having now described my invention and a way of practising the same, although 60 without attempting to include all methods of manufacturing, or all of the uses of the fabric, what I claim is:

1. Sheet material formed of two fabrics woven simultaneously and having parallel 65 strips of soft, fluffy material incorporated therein during the process of weaving and having binding warps uniting the fabrics between the said strips.

2. Sheet material formed of two fabrics 70 woven simultaneously and having parallel strips of soft, fluffy material incorporated therein during the process of weaving and having binding warps uniting the fabrics between the said strips and reinforcing 75 threads extending longitudinally of the strips of soft, fluffy material.

3. The method of making woven sheet material, consisting in simultaneously weaving two fabrics, introducing soft, fluffy material 80 between said two fabrics, and uniting the two fabrics by binding warps during the process of weaving said fabrics.

In testimony whereof I have affixed my signature, in presence of two witnesses.

GEORGE J. BICKNELL.
